PICTURE SCANNING AND ASSEMBLING DEVICE FOR TELEVISION AND PICTURE TRANSMISSION

Application filed September 17, 1930, Serial No. 482,612, and in Germany August 5, 1930.

Picture scanning and assembling devices (for instance Nipkow disc, Weiller's rotating mirror, or the like) as hitherto known have the disadvantage that when a larger number 5 of picture elements are used their diameter becomes so large that they can no longer be used in practice. At the same time, the dimensions of the holes in the case of Nipkow discs become so small that they can no longer 10 be made sufficiently accurate.

Assembling devices are also known in which a rotary system comprising a number 15 of mirrors corresponding to the number of picture lines is provided, which mirrors are arranged next to one another along an axis of rotation, being distributed at equal angular distances from one another over the range of rotation. In these known picture assembling devices a source of light in the form of a 20 point, which is modulated by the photoelectric currents, is projected upon a screen through the intermediary of condensers. Such an arrangement, however, is practicable only when the number of picture lines is 25 small. The arrangement completely fails when the number of lines is increased, since the angles which are enclosed by the individual mirror surfaces then become so small that the beam of light which appears on the reflecting surface with a width several times 30 larger than that of the source of light employed is reflected at the same time by a number of mirrors, so that a number of points of light appear on the screen, whereby the 35 picture becomes useless.

These drawbacks are avoided according to the present invention by this that subjective observation is substituted for the projection 40 and that an elongated or linear source of light is used instead of a point of light, for instance a glow tube which is arranged parallel to the axis of rotation of the mirror system at a suitable distance therefrom. Moreover, for the subjective observation, 45 it is necessary that the minimum length of the individual mirrors shall be equal to the length of the picture lines.

The invention is illustrated diagrammatically and by way of example in the accompanying drawings, in which

Figure 1 shows in perspective view the essential parts of the television receiving apparatus for the direct viewing of the picture on the picture assembling device.

Figure 2 is a plan view of a television receiving apparatus provided with a device for phase adjustment.

Figure 3 is a front view of the device shown in Figure 2.

Referring to Figure 1, 1 is a rotor and 2 the stator of a phonic wheel, the sprindle 3 of which carries a picture assembling device 4 to which the present invention relates.

For the sake of clearness, the device illustrated in the example shown in the drawings 65 comprises, according to the selected number of picture lines, viz. only six picture lines, six juxtaposed plates 4a-4f, each one of which is provided with a mirror surface 4u-4z. The mirror surfaces are displaced relatively 70 to one another through an angle of 60°, so that they are uniformly distributed on the periphery of the picture assembling device. The mirror 4z cannot be seen in Figure 1, 75 since it is covered by the parts which lie in front. An elongated or linear source of light 5 is arranged near the mirror cylinder, the said source of light being in the present case a glow discharge lamp, the two electrodes of which consists of two wires 6 and 7 respectively to which the received photoelectric 80 currents are applied. When the phonic wheel 1 runs synchronously with the picture scanning device of the transmitter at such a speed that the mirror cylinder 4 makes one complete 85 revolution of 360° during the period of transmission of each individual picture, the eye 9 of the observer sees when the cylinder 4 rotates in the direction of the arrow 10 a point of light representing the corresponding picture element, which point of light runs consecutively on the mirrors 4a-4f from the left- to the right-hand-side, whereby an assembling of the picture is obtained. The point of light appears as a reflected picture of the 90 section of the glowing tube 5 corresponding to the respective individual mirror and the intensity of its brightness corresponds to the brightness at the particular moment of the light radiated from the glow tube. The use 95

100

of any system of lenses for attaining this result is superfluous.

The picture cylinder carries next to one another so many individual mirrors as there are picture lines in the picture. Let us assume that we have a picture comprising 30 picture lines. In this case 30 mirrors, $4u$, $4v$, etc., are arranged next to one another, which mirrors are distributed over the periphery of the picture cylinder at equal angular distances, that is to say the reflecting surfaces in the case of 30 picture lines enclose an angle of $360^\circ \div 30 = 12^\circ$.

In the arrangement illustrated in Fig. 1, the mirrors have a width which is limited by the width of the picture lines; the length thereof may, however, vary as desired, being above the minimum length determined by the length of the picture element. Preferably the length of the mirror is made substantially equal to the length of the picture lines, as can be seen from Figure 1.

The adjustment of the phase can be effected in a very simple manner by this that the mirrors which are arranged at equal angular distances from one another are provided in a greater number than that corresponding to the number of the picture lines over an angle exceeding 360° , that is to say the screw, which is so to say formed by the mirrors, is continued beyond a full revolution. The phase adjustment can then be effected simply by a displacement of the mirror system in the direction of the axis of rotation.

One arrangement for carrying this idea into effect is illustrated by way of example in Figures 2 and 3, it being assumed that in this case use is made of a picture having 20 picture lines. Accordingly 20 separate mirrors 20 are employed, which are distributed over the normal length 21 of the picture cylinder, being arranged next to one another at equal angular distances. In order to render possible the phase adjustment, the picture cylinder is continued by another picture cylinder of the same construction. In other words, a similar system of 20 mirrors 22 forms a continuation of the mirror system 20. Thus the total length of the mirror cylinder is double the length of the ordinary mirror cylinders.

In front of the mirror cylinder which receives its illumination, for instance in the manner indicated in Figure 1, there is provided a mask 23 corresponding to the picture dimensions. The mirror cylinder is displaceably mounted on the shaft 25 which is driven by the phonic wheel 24, the displacement being effected axially in each direction to the extent of half the width of the picture. This displacement enables the right phase to be obtained.

In order to effect the displacement in the arrangement illustrated in the drawings, an annular track 26 is provided at the end of the mirror cylinder, the said track being in-

tended to receive two rollers 27 which are secured to the ends of the prongs of a forked member 28. The latter member is secured to a screw nut 29 which can be axially displaced on a rotary but axially fixed screw 30 by the rotation of the latter by means of a crank handle 31, being secured against rotation by means of a guiding rod 32.

What we claim is:—

1. An apparatus for television reception and the reception of electrically transmitted pictures comprising in combination a linear source of light intended to be controlled by the received currents and a rotary system of mirrors, the number of which corresponds to the number of the picture lines, the said mirrors being arranged next to one another along an axis of rotation and distributed at equal angular distances from one another over the range of rotation, the linear source of light being arranged to lie parallel to the said axis of rotation and to produce its image in the system of mirrors direct without the interposition of any optical system, and the minimum length of the individual mirrors being equal to the length of the picture lines.

2. A picture assembling device as claimed in claim 1 and in which the individual mirrors which are arranged at equal angular distances from one another are continued beyond a total angle of 360° , in combination with means for displacing the whole mirror system in the direction of the axis of rotation for the purpose of phase adjustment.

In testimony whereof we have signed our names to this specification.
